UNITED STATES PATENT OFFICE.

NATHAN BUSHWICK, OF MASPETH, NEW YORK.

FOLDING HAND-BAG.

1,143,171.

Specification of Letters Patent. Patented June 15, 1915.

Application filed April 6, 1914. Serial No. 830,052.

To all whom it may concern:

Be it known that I, NATHAN BUSHWICK, a citizen of the United States, residing at Maspeth, in the county of Queens and State 5 of New York, have invented certain new and useful Improvements in Folding Hand-Bags; and I do declare the following to be a full, clear, and exact description of the invention; such as will enable others skilled in 10 the art to which it appertains to make and use the same.

This invention relates to improvements in hand bags or satchels of that class which may be converted into different sizes by 15 folding and fastening its parts.

The object of the invention is to provide a folding handbag capable of being made either large or small accordingly as it is to be used, and which will present a neat appearance in either folded or extended positions.

With this and other objects in view, the invention consists of certain novel features of construction, and the combination and 25 arrangement of parts, as will be more fully described and claimed.

In the accompanying drawings: Figure 1 represents a perspective view of one form of the invention folded to form a hand bag 30 of ordinary size having flap covered pockets on its opposite faces. Fig. 2 is a perspective view with one of the flaps in open position and the pocket ready to receive an article. Fig. 3 is a perspective view in open position taken from the opposite side. Fig. 4 is a transverse section in the position shown 35 in Fig. 3. Fig. 5 is a longitudinal irregular section taken on the line 5—5 of Fig. 4. Fig. 6 is a perspective view of the device 40 shown used as a Gladstone bag. Fig. 7 is a transverse section of the bag as shown in Fig. 6. Fig. 8 is a longitudinal section on line 8—8 of Fig. 7. Fig. 9 is a diagrammatic perspective of the blank from which 45 said bag is formed. Fig. 10 is a perspective view of another form of the invention shown in folded position. Fig. 11 is a perspective view taken from the opposite side. Fig. 12 is a central longitudinal section thereof; Fig. 13 is a longitudinal sectional view 50 taken at one side of the center. Fig. 14 is a transverse section taken on line 14—14 of Fig. 13; Fig. 15 is a perspective view of the bag in the form of a Gladstone bag. Fig. 55 16 is a central longitudinal section taken on line 16—16 of Fig. 17. Fig. 17 is a trans-

verse section taken on line 17—17 of Fig. 16. Fig. 18 is a fragmentary plan view of the overlapping bottom sections. Figs. 19 and 20 are diagrammatic views of the blanks, 60 showing opposite sides of the blanks.

In the embodiment illustrated in Figs. 1 to 4, this improved bag comprises a main bottom section 1 having auxiliary bottom sections 2 and 3 foldably connected with the 65 opposite side edges thereof. The auxiliary section 2 is permanently connected with the main section 1 at one side edge and the section 3 is detachably connected therewith at its other side edge, said section 3 having a 70 flap 4 provided on its inner face near its free edge with longitudinally spaced fastening elements 5 and said flap is adapted to overlap the outer face of the free edge of the main section, which latter is provided with 75 complementary fastening elements 6 for engagement by the elements 5 of the auxiliary section 3. Both of the auxiliary sections 2 and 3 are provided with end flaps 7 having fastening elements 8 on their outer faces for 80 a purpose to be described.

The main section 1 is provided with end wings or flaps 9 provided around their edges with fastening elements 10 for coöperation with complementary elements on parts to be 85 described. The auxiliary bottom section 3 is flexibly connected at the edge opposite its flap carrying edge with the bottom edge of a side member 11, said side member being equipped near its upper or outer free edge 90 with fastening elements 12 and at its central portion with a fastening element 13 for a purpose to be described. Another side member 14 is flexibly connected at its lower edge 95 with the edge of the auxiliary bottom section 2 opposite that to which the main bottom section 1 is connected, and this side member 14 is provided on its outer face near its lower edge with a plurality of longitudinally spaced fastening elements 15, and at 100 its center with a fastening element 16, for purposes to be described.

Foldable end members 17 and 18 connect the ends of the side members 11 and 14, the end member 17 being attached at one end 105 with the end of the side member 14 and the other end of said end member 17 is attached to one end of the side member 11, the member 18 being similarly attached to the opposite ends of the side members 11 110 and 14, and as both of these end members are similarly constructed, one only will be

described in detail. These members 17 and 18 each comprise two sections 19 and 20 flexibly connected at one edge, said sections being of the same width and their united 5 width corresponding to the width of the auxiliary bottom section 2. These sections 19 and 20 correspond in height to the height of the end members 11 and 14 and the free edge of each section 20 is secured to the 10 opposite ends of the member 14 by a flexible strip of leather or any other suitable material. The flexible connection of the strips 19 and 20 permits them to be folded inwardly and lie one upon the other to provide for the closing of the satchel such as 15 is ordinary in devices of this character. A partition 21, corresponding in shape and size to the side members 11 and 14 is connected at its opposite ends to the free edges 20 of the sections 19 of the end members 17 and 18, the bottom edge of said partition being free and its top edge provided with a flap 22 preferably made integral therewith and provided at its free edge with a 25 fastening element 23 adapted to engage the fastening element 13 disposed at the center of the outer face of the side member 11 and by means of which the pocket formed between the side member 11 and the partition 21 is closed at its upper end. Straps 24 are secured to the inner face of the partition 21 near its upper edge at the point of attachment of the flap 22 and are equipped with fastening elements 25 adapted to 30 operate with the fastening elements 12 on the outer face of the side member 11 for fastening the partition to said side member when the device is in extended position to form a Gladstone bag as will be herein- 35 after more fully described. Foldable end members 26 and 27 connect the opposite ends of the partition 21 with the opposite ends of the side member 11 and each of these members as shown, comprises three 40 triangular members 28, 29, and 30.

The sections 28 and 29 of the end members 26 and 27 are preferably in the form of right angled triangles with one of the straight edges of the section 28 connected 45 with the end of the side member 11 and the corresponding straight edge of the section 29 flexibly connected with the end of the partition 21, the bases of said triangles being disposed upwardly and forming the top edges of the end members. Secured to the oblique sides of these triangular members 28 and 29 is the equilateral triangular section 30, the vertex of which is arranged 50 at the junction of the two sections 28 and 29 substantially midway the width of the end member formed thereby. The base of the section 30 is disposed at the bottom of the end member of which it forms a part, and extends the full width of said end member, 55 being secured to the vertexes or points of the

members 28 and 29 at the bottom of the end member of which these sections form a part, and provided with fastening elements 31 which are adapted to be engaged by the complementary fastening elements on the 70 free ends of the flaps 9 when the device is opened up to form a Gladstone satchel or grip.

The section 30 is creased from its vertex at the top of the end member of which it 75 forms a part to a point midway the ends of its base and the end sections 28 and 29 are creased from a point arranged midway the width of their bases arranged at the upper end of the end members of which 80 they form a part, on a line extending to the points of said sections disposed at the bottom of said end member whereby these sections 28 and 29 and the section 30 may be folded inwardly to bring the edges of 85 the partition 21 and the side member 11 into contact when the device is folded to provide a handbag of smallest size into which the device is capable of being made, the sections 19 and 20 being similarly folded 90 when the bag is collapsed. A flap 32 is connected with the upper end of the partition 21 on the side opposite to that on which the flap 22 is connected and is adapted to extend oppositely to said flap 22 and to 95 fit over and close a pocket formed by the side member 14 and the partition 21. This flap 32 has a fastening element 33 adapted to cooperate with the fastening element 16 on the outer face of the side member 14, 100 whereby said flap is secured in closed position. A handle 34 is secured to the upper edge of the partition 21 between the flaps 22 and 32 and is designed for use in carrying the satchel or hand bag when in either 105 folded or extended positions.

When the device is opened up with all of the detachable parts disconnected and it is desired to form a satchel or Gladstone bag which is the largest size into which the device is to be made,—the flap 4 on the auxiliary bottom section 3 is lapped over the lower face of the main bottom section 1 and the fastening elements 5 thereof are engaged with the complementary fastening elements 110 6 on the outer faces of said main section 1 thereby forming the bottom proper for the Gladstone bag. The fastening elements on the opposite ends of the flaps or wings 9 connected with the opposite ends of the main section 1 are then engaged with the complementary fastening elements on the flaps 7 at the ends of the auxiliary bottom sections 2 and 3 and when in this position, these auxiliary bottom sections form upright side members for the Gladstone bag or satchel, being connected by the end flaps 9 which are also arranged upright in planes at right angles to the main bottom section 1. The 115 fastening elements on the free upper edge 120 125 130 135

of the flap 9 are then engaged with the complementary fastening elements at the lower end of the sections 30 of the end members 26 and 27 whereby said sections 30 are held in 5 extended open position. The sections 28 and 29 of the end members are then folded inwardly and the fastening elements 12 at the upper end of the side member 11 are engaged by the coöperating or complementary members on the straps 24 secured to the 10 partition 21 near its upper end, whereby said side member 11 is held connected with the upper end of said partition and forms one of the oblique side members of the Gladstone bag, the end members of which are triangular and are formed by the sections 30 of the end members 26 and 27. When the bag is in this position, the pocket formed by the side member 14 and the partition 21 may be 15 used and articles may be passed to the other side of the satchel below the partition 21, which, when the parts are so arranged, is disposed at a point some distance above the main bottom section 1, the distance being 20 equal to the width of the auxiliary bottom sections 2 and 3, which then constitute the upright portions of the side members of the body of the satchel. The straps 24 which pass over the upper edge of the member 11 25 hold said parts securely in adjusted position in the shape in which it is desired to form the bag, the end flaps 9 coöperating therewith to so hold the parts, these end flaps being designed to prevent the lateral 30 collapse of the bag, and their length determines the width of the bag.

The bag being in extended position, as shown in Fig. 6, and it is desired to reduce the size thereof to form a small handbag, 40 the straps 24 are first disengaged from the side member 11 and the end flaps 9 are disconnected from the end members 26 and 27 and from the flaps 7 at the ends of the auxiliary bottom sections 2 and 3. The flap 4 is 45 then disconnected from the main bottom section 1 and the device is then ready to be collapsed or folded to produce a small handbag. This is accomplished by first folding the end flaps 9 inwardly against the main 50 bottom section 1 and then passing said bottom section upwardly into the bag and lapping the auxiliary bottom section 3 over the auxiliary section 2 and securing the flap 4 to the side member 14 by engaging the fastening elements 5 thereof with the fastening elements 15 on said side member. When the parts have been so disposed, the main bottom section 1 will be placed against the inner face 55 of the side member 11 and the end flap 7 on the auxiliary bottom section 3 will be folded inwardly between said section 3 and the other auxiliary section 2 which it overlaps. The flaps 7 on the auxiliary bottom section 2 are then extended upwardly at right angles to 60 said section and engaged with the end mem-

bers 17 and 18 by connecting the complementary fastening elements on said flap 7 and on the lower edges of said end members. This positioning of the parts, forms a pocket between the side member 14, the partition 21 70 and the end members 17 and 18 with the overlapping bottom sections 2 and 3 forming the bottom thereof. If desired, the partition 21 may be provided on the face thereof arranged opposite the inner face of the 75 member 14 with a pocket 35. Another pocket is also formed when the parts are in this position between the side formed by the overlapping members 11 and 1 and the face of the partition 21 opposite to that 80 which forms the other pocket and this pocket is adapted to be closed by folding the end members 26 and 27 on the creases above described, and then connecting flap 22 with the side member 11 by engaging the coöperating 85 fastening element on these two members and the device will then be in the position shown in Fig. 1, as a small hand bag having two pockets on its opposite faces closed respectively by the flaps 22 and 32. 90

In the embodiment illustrated in Figs. 10 to 20, a bag is shown, capable of being extended and the parts arranged to form a Gladstone satchel or bag and to be collapsed and folded to form a small hand bag 95 such as are carried by women and girls for every day use. This bag is composed of two sections 40 and 41 connected by foldable end members 42 and 43 hereinafter described more fully in detail. 100

Each of the sections 40 and 41 comprises a bottom member or section 44, or 44' a side member 45 or 45', and an intermediate member 46 or 46', formed of stiff material and flexibly connected. The section or member 44 forms one-half of the bottom of the bag when it is arranged in the form of a satchel known as the Gladstone. This bottom section 44 is provided along its free edge for about one-half of its length, more or less, 110 with a flange or lip 47 extending in the same plane as the body portion of said member and forming a fastening tongue having its inner end inclined downwardly and inwardly for interlocking engagement with a 115 similarly shaped tongue 47' on the corresponding bottom member 44' of the section 41. A plurality of longitudinally spaced fastening elements 48, two of which are arranged adjacent the inclined end of the 120 tongue 47, are adapted for engaging complementary members 48' on the corresponding bottom member of the section 41, as will be hereinafter described. This bottom member 44 is provided at its opposite ends with 125 wings 49 and 50, the wing 49 being the same width as the section 44 and flexibly secured at one end thereto with the inner portion of its upper edge arranged flush with the edge 130 of the section 44 to which it is connected.

The remaining portion of the lower or under edge of the wing 49 is extended to form a lip 49^a having a tongue 49^b at its inner end, said tongue inclining inwardly and upwardly, and is adapted for interlocking engagement with a correspondingly shaped tongue 50^b on the wing of the bottom member of the section 41. Each of the wings 49 and 50 has a triangular opening 51 therein for a purpose to be described,—the base of said triangular opening being preferably arranged parallel with the side edges of the wing. The lip of the wing 49 extends from its free outer end edge inwardly to a point 15 mid-way the length of said wing, and the lip on the wing 50 is similarly arranged. The only difference in the two wings is that the wing 50 terminates at the base of the tongue 47 on the section 44, being of the same width as said section at its other end and of the same width as the wing 49.

The intermediate section 46 which connects the bottom section 44 with a side member or section 45 is provided at its opposite ends 25 with flaps 52 tapering toward their free ends and terminating in pointed tongues 53 of a width corresponding to the triangular openings in the wings 49 and 50, said tongues preferably being substantially the same 30 width as the bases of said triangles to permit them to completely fill the space formed by the triangular openings when the flaps are engaged with said wings, as will be herein-after more fully described. The side members 45 and 45' of the sections 40 and 41 are connected at their opposite ends to the opposite ends of the foldable end members 42 and 43 and said side members are exactly alike, except that one of said members has 35 two flaps 54 and 55 disposed at its opposite ends on their outer or upper edges, while the side member of the section 41 has a centrally disposed flap 56 which is of substantially the same length as the space between the flaps 40 54 and 55 of the side member of the section 40 and is adapted to extend over and be connected with the side section carrying the flaps 54 and 55 by suitable fastening elements carried respectively by said flap and 45 the side section which it overlaps, the flaps 54 and 55 being designed to overlap the section which carries the flap 56 and to be detachably connected therewith by complementary fastening elements carried respectively by the flaps and the side member of 55 the section 40.

The bottom member 44' of the section 41 is similar in construction to the bottom member 44 of the section 40, except that the tongue 47' on the member 44 is disposed at the end opposite to that on which the tongue of the member 44 is disposed to adapt them to be interlockingly engaged when the bag is set up for use as a satchel or Gladstone, and 60 when these tongues are interlocked, the bot-

tom sections 44 and 44' are detachably connected by the co-operating fastening elements 48 and 48' carried thereby, the tongue carrying lip on section 44' underlaps the edge of the section 44, and the tongue on the 70 section 44 underlaps the edge at the opposite end of the section 44', the lips of the two bottom sections or members being provided with stud carrying elements of the fastening members, while the edges which have no 75 tongues carry the socket members which are adapted to be engaged with the stud members on the adjacent section.

The side member 45 of the section 40 is preferably provided on its outer face with 80 a pocket 57 which is adapted to be closed by the flap 56 on the side member 45' of the section 41. The end members 42 and 43 are similarly constructed and they are also similar in construction to the end members 25 26 and 27 of the device shown in Figs. 1 to 9, the only difference being that the right angle triangles at the opposite ends of the end members are not creased to be folded, the only folds being necessary are those 90 formed at the junction of the right angle triangular members and the equilateral triangular member, said equilateral triangular member being creased from its apex to a point mid-way its base. 95

Straps 58 and 59 are secured to the outer face of the side member 45 of the section 40, being longitudinally spaced from each other, and here shown secured to said member by stitching. These straps merge at their upper ends into a handle 60 which projects beyond the edge of the member 45. These straps are of a length adapted to extend partially around the satchel when in extended position, and are adapted to be detachably 105 secured at their free ends to straps 61 and 62 secured to the outer face of the side member 45' of the section 41, said straps 61 and 62 being positioned to aline with the straps secured to the other side member and they 110 also merge at their upper ends into a handle 60' which projects beyond the outer edge or top of the side members 45', and is adapted to be grasped together with the handle 60 for carrying the bag. The free ends of 115 these straps 61 and 62 are provided with fastening elements complementary to those carried by the straps 58 and 59 and which are adapted to be engaged and form bracing means for the bag when in extended position. The straps 58 and 59 are provided near the lower edge of the bottom of the side member 45 with fastening elements 63 with which the fastening elements on the ends of the straps 61 and 62 are adapted to be engaged when the satchel is in collapsed or folded condition to form a hand bag. 120

When the parts of the satchel are disconnected and it is desired to form a large satchel or Gladstone bag, the tongues on the 125

free edges of the bottom sections 44 and 44' are interlockingly engaged and the fastening elements of said sections are also connected, the two sections 44 and 44' when so connected forming the bottom of the satchel. The wings 49 and 50 on the ends of the sections 44 and 44' are then swung upwardly into a plane at right angles to the sections with which they are connected and the tongues on the adjacent edges thereof are interlockingly engaged. The tongues 53 on the flaps 52 carried by the intermediate sections 46 and 46' are then passed through the triangular openings 51 in the wings carried by the bottom sections and the fastening elements on these tongues are engaged on the outer faces of said wings thereby securely holding the wings connected to each other and to the intermediate sections 46 and 46' which form the upright side members of the satchel when arranged in this position. The fastening elements carried by the ends of the wings 49 and 50 are then engaged with the complementary fastening elements carried on the lower edge of the end members 42 and 43. These end members 42 and 43 are then folded inwardly and the flaps 54 and 55 on the side section 45 are lapped over the upper edge of the section 45' and the fastening elements on the two sections are engaged, thereby securing the two sections 40 and 41 together in operative position to form a satchel or Gladstone bag, the flap 56 being passed over the upper edge of the section 45' and the pocket on its outer face and secured in closed position by the complementary fastening members carried by said flap and by the pocket. The straps 58 and 59 are then passed transversely around the satchel and the fastening elements at the free ends thereof are connected with the fastening elements at the ends of the straps 61 and 62 and the satchel is thus braced ready for use, without danger of its coming apart when heavily loaded.

When the large bag shown in Fig. 15 is desired to be reduced in size to form a small hand bag, the flaps 54 and 55 and 56 are first disengaged from the sections with which they are connected, the straps 58 and 59 are disconnected from the straps 61 and 62 and the wings 49 and 50 are disengaged from the end members 42 and 43, the tongues 53 of the flaps 52 are then disconnected and the tongues withdrawn through the openings in said wings. The bottom sections 44 and 44' are then disconnected by releasing their fastening elements and unlocking the engaging tongues thereof, and the device is ready to be folded to form a small hand bag. This is accomplished by folding the wings 49 and 50 of each of the sections 40 and 41 inwardly against the section to which they are connected, the flaps 50 and 52 are then similarly folded against the inner faces of the

intermediate sections and the bottom section or member is folded inwardly against the intermediate section, and the so-folded bottom and intermediate sections are then folded flat against the inner face of the side member of the section. The end sections 42 and 43 are then folded inwardly on the crease which extends transversely across said end members at a point mid-way the ends thereof, said end members extending between the folded parts of the two sections 40 and 41 and they are secured in this collapsed position by the flaps 54 and 55, which are engaged with the fastening elements on the other side section, the flap 56 being engaged with its coöperating element on the pocket of the section carrying the flaps 54 and 55. The free ends of the straps 61 and 62 are then engaged with the fastening elements near the bottom edges of the section 45, the ends of the straps 58 and 59 being folded or inclosed within the hand bag, and when in this position, the handles 60 and 60' may be grasped by the user and the hand bag, in reduced form, conveniently carried from place to place, two pockets for use being provided within the satchel and one on its outer face.

I claim as my invention:

1. A folding and extensible handbag comprising a bottom member, side members, and intermediate members disposed between and flexibly connected with said side and bottom members, foldable end members connecting said side members and means for detachably connecting said end and bottom members.

2. A folding and extensible handbag comprising a bottom member, side members, and intermediate members disposed between and flexibly connected with said side and bottom members, foldable end members connecting said side members, means for detachably connecting said end and bottom members, and flaps adapted to be engaged with the opposite side members for closing said bag when in either folded or extended position.

3. A folding and extensible handbag comprising a bottom member, side members, and intermediate members disposed between and flexibly connected with said side and bottom members, foldable end members connecting said side members, said bottom member having wings flexibly connected with its opposite ends, means on said intermediate members for detachably engaging said wings when the bag is extended, and means for detachably connecting said end members and wings.

4. A folding and extensible handbag comprising a bottom member, side members, and intermediate members disposed between and flexibly connected with said side and bottom members, foldable end members connecting said side members, and means for detachably connecting said end and bottom mem-

- bers, said bottom members being detachably connected with one of the intermediate members and foldable into the bag when collapsed.
5. A folding and extensible handbag comprising a bottom member, side members, and intermediate members disposed between and flexibly connected with said side and bottom members, said bottom member having wings 10 flexibly connected with the opposite ends thereof, flaps flexibly connected with the opposite ends of said intermediate members, fastening elements for connecting said flaps with the ends of said wings when the bag is extended and flaps for closing the upper 15 ends of said bag when in either extended or collapsed position.
6. A folding and extensible handbag comprising a bottom member, side members, and intermediate members, said intermediate members being arranged between and flexibly connected with said side and bottom members, one of said intermediate members having a flap detachably engaged with said 20 bottom member, foldable end members connecting said side members, and means for closing and connecting the upper ends of 25 said side members.
7. A folding and extensible handbag comprising a bottom member, side members, and intermediate members, said intermediate members being arranged between and flexibly connected with said side and bottom members, one of said intermediate members 30 having a flap detachably engaged with said bottom member, foldable end members connecting said side members, a longitudinally extended partition secured at its opposite ends to said foldable end members intermediately of their length, said partition being 35 of a width to correspond with the width of said end members, and flaps carried by said partition for closing the bag and holding the members in adjusted position.
- 40 8. A folding and extensible handbag comprising a bottom member, side members, and intermediate members, said intermediate members being arranged between and flexibly connected with said side and bottom members, one of said intermediate members 45 having a flap detachably engaged with said bottom member, foldable end members connecting said side members, a longitudinally extended partition secured at its opposite ends to said foldable end members intermediately of their length, said partition being 50 of a width to correspond with the width of said end members, flaps carried by said partition for closing the bag and holding the members in adjusted position.
- 55 9. A folding and extensible handbag comprising a bottom member, side members, and intermediate members, said intermediate members being arranged between and flexibly connected with said side and bottom members, one of said intermediate members 60 having a flap detachably engaged with said bottom member, foldable end members connecting said side members, a longitudinally extended partition secured at its opposite ends to said foldable end members intermediately of their length, said partition being 65 of a width to correspond with the width of said end members, flaps carried by said partition for closing the bag and holding the members in adjusted position, said partition having straps on its inner face on its upper end provided with fastening elements, and complementary fastening elements arranged on the outer face of the adjacent side member near its upper end whereby said parti- 70 75 80 85 90 95 100 105 110 115 120 125 130
- tion is connected with said side members when the bag is in extended position.
10. A folding and extensible handbag comprising a bottom member, side members, and intermediate members, said intermediate members being arranged between and flexibly connected with said side and bottom members, one of said intermediate members having a flap detachably engaged with said bottom member, foldable end members connecting said side members, a longitudinally extended partition secured at its opposite ends to said foldable end members intermediately of their length, said partition being of a width to correspond with the width of said end members, and flaps carried by said partition for closing the bag and holding the members in adjusted position, said partition having flaps at its upper end extending in opposite directions and adapted to overlap the respective side members, said side members and flaps being provided with cooperating fastening elements for securing them together.
11. A folding and extensible handbag comprising a bottom member, side members, and intermediate members, said intermediate members being arranged between and flexibly connected with said side and bottom members, one of said intermediate members having a flap detachably engaged with said bottom member, foldable end members connecting said side members, a longitudinally extended partition secured at its opposite ends to said foldable end members intermediately of their length, said partition being of a width to correspond with the width of said end members, flaps carried by said partition for closing the bag and holding the members in adjusted position, said foldable end members being each composed of two right angle triangular members having their bases disposed upwardly and their points downwardly, an equi-lateral triangular member arranged between said first mentioned members with its base forming the lower edge of a portion of the end member, said equi-lateral triangular member having a crease extending from its apex to its base at a point midway the lower corners thereof, said side members being creased from the lower points at their ends to a point midway of their width of their bases, and a strip secured at one edge to one of said right angular triangles and at its other edge to one of the side edges of one of said side members, said strip being creased longitudinally intermediately of its width to adapt it to fold inwardly.
12. A folding and extensible handbag comprising a bottom member, side members, and intermediate members, said intermediate members being arranged between and flexibly connected with said side and bottom members, one of said intermediate mem-

bers having a flap detachably engaged with said bottom member, foldable end members connecting said side members, a longitudinally extended partition secured at its opposite ends to said foldable end members intermediately of their length, said partition being of a width to correspond with the width of said end members, flaps carried by said partition for closing the bag and holding the members in adjusted position, said foldable end members being each composed of two right angle triangular members having their bases disposed upwardly and their points downwardly, an equi-lateral triangular member arranged between said first mentioned members with its base forming the lower edge of a portion of the end member, said equi-lateral triangular member having a crease extending from its apex to its base at a point midway the lower corners thereof, said side members being creased from the lower points at their ends to a point midway of their width of their bases, and a strip secured at one edge to one of said right angular triangles and at its other edge to one of the side edges of one of said side members, said strip being creased longitudinally intermediately of its width to adapt it to fold inwardly, and a partition arranged in said bag and connected at its opposite ends to the inner edge of said creased strip and to the triangular member connected therewith.

12. A folding and extensible handbag comprising a rectangular bottom member having rectangular wings flexibly secured to the opposite ends thereof, an intermediate member flexibly and permanently secured to one side edge of said bottom member and provided at its opposite ends with semi-circular flaps, a side member flexibly secured to the other side edge of said intermediate member and provided on its outer face near its lower end with a plurality of longitudinally spaced fastening elements, another intermediate member detachably connected with the free edge of said bottom member and having semi-circular flaps at its oppo-

site ends, a side member connected with the other edge of said intermediate member and having foldable end members connecting the ends of said side members, said flaps and wings having coöperating fastening elements for securing them together when the device is in extended position.

13. A folding and extensible handbag comprising a rectangular bottom member having rectangular wings flexibly secured to the opposite ends thereof, an intermediate member flexibly and permanently secured to one side edge of said bottom member and provided at its opposite ends with semi-circular flaps, a side member flexibly secured to the other side edge of said intermediate member and provided on its outer face near its lower end with a plurality of longitudinally spaced fastening elements, another intermediate member detachably connected with the free edge of said bottom member and having semi-circular flaps at its opposite ends, a side member connected with the other edge of said intermediate member and the foldable end members connecting the ends of said side members, said flaps and wings having coöperating fastening elements for securing them together when the device is in extended position, said detachable intermediate member having a longitudinally extending flap flexibly connected to its free edge and provided with coöperating fastening elements, said bottom member having fastening elements on its outer face near its free edge, said flap being designed to engage the fastening elements on said bottom member when the device is extended and to engage the fastening elements on said side member when the device is collapsed.

In testimony whereof I have hereunto set my hand in presence of two subscribing witnesses.

NATHAN BUSHWICK.
